US00D868771S

(12) **United States Design Patent** (10) Patent No.: **US D868,771 S**
(45) Date of Patent: ** Dec. 3, 2019

(54) **SERVER FOR DATA**

- (71) Applicant: **KONICA MINOLTA, INC.**,
Chiyoda-ku, Tokyo (JP)
- (72) Inventors: **Masakazu Nagano**, Nishinomiya (JP);
Yu Iritani, Tokyo (JP); **Thomas Edward Keen**, London (GB); **Nicholas Woodley**, London (GB); **Astrid Nathalie Xavier Vanhuyse**, London (GB); **Manon Bourette**, London (GB)
- (73) Assignee: **KONICA MINOLTA, INC.**,
Chiyoda-Ku, Tokyo (JP)

(**) Term: **15 Years**

(21) Appl. No.: **29/654,286**

(22) Filed: **Jun. 22, 2018**

(30) **Foreign Application Priority Data**

CLAIM

The ornamental design for a server for data, as shown and described.

DESCRIPTION

FIG. 1 is a front elevational view of a server for data showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view thereof.

1 Claim, 5 Drawing Sheets
